UNITED STATES PATENT OFFICE.

DAVID H. LEVETT, OF PHILADELPHIA, PENNSYLVANIA.

MIXING-MACHINE.

SPECIFICATION forming part of Letters Patent No. 296,338, dated April 8, 1884.

Application filed July 23, 1883. (No model.)

To all whom it may concern:

Be it known that I, DAVID H. LEVETT, a citizen of the United States, residing in the city and county of Philadelphia, State of Pennsylvania, have invented a new and useful Improvement in Mixing-Machines, which improvement is fully set forth in the following specification and accompanying drawings, in which—

10 Figure 1 is a side elevation, partly broken away, of a mixing-machine embodying my invention. Fig. 2 is a section in line xx , Fig. 1.

Similar letters of reference indicate corresponding parts in the two figures.

15 My invention consists of a drum or cylinder, and beaters thereon rotating in reverse order, thus occasioning a movement of materials in opposite directions, and a thorough inter-mixture of the same, the construction of parts 20 being hereinafter fully set forth and definitely claimed.

It also consists of the construction of beaters of a mixing-machine, whereby they operate most effectively in causing an intermixture 25 of the materials, the latter being more particularly of a plastic nature, to which, however, the invention is not limited.

Referring to the drawings, A represents a drum, cylinder, or receiver for the materials 30 to be mixed; B, the shaft thereof; B', the bearings of the latter, and C the beaters, which are secured to the shaft. The drum is mounted loosely on the shaft B, and has secured to the outside of one of its heads a bevel-pinion, 35 D, which freely encircles said shaft and gears by means of an idler, E, with a bevel-pinion, F, which latter is firmly connected with said shaft B, the idler being properly mounted.

Power is applied to the shaft in any suitable 40 manner, a crank-wheel being shown in the present case, the rotation of the shaft being imparted to the beaters, and, owing to the gearing D E F, also to the drum A, it being seen that the movement of the beaters and drum 45 is in reversed direction, by which provision the materials in the drum are subjected to the reverse actions of the beaters and drum, and thus forcibly agitated and thrown around in opposite directions, whereby they are thoroughly intermingled and mixed. In order to 50 increase the effectiveness of the beaters, they are formed throughout their lengths at inter-

vals with cross-bars a, and on their ends with heads b, which bars and heads may be integral with the beater-arms or separate pieces attached thereto. The cross-bars of each arm alternate with those of the adjacent arm, thus breaking joints between the adjacent cross-bars, and forming somewhat zigzag passages between the same, the effect whereof is to direct the materials to be mixed in numerous streams or currents, and change the directions thereof, thus effectually mixing the materials. This is assisted by the end heads, b, which throw the materials from the periphery of the drum, 60 and in a measure act as scrapers thereat, and thus the beaters cause the materials to be kept in constant agitation from center to periphery. The drum is provided with a removable section or lid, G, for supplying the same with materials to be mixed, and discharging the mixed material therefrom, said lid, when closed, being secured in any suitable manner. The head A of the drum is divided, as at d, so as to be readily removed for access to the interior of 75 the drum at the end thereof. When said divided or sectional head is fitted in position on the end of the drum, it is securely held by means of bolts e, which are fixed to the drum, and enter eyes f, fixed to the sections of the 80 head, the ends of the bolts having fitted to them nuts g, which may be tightened, causing the head to be firmly clamped to the drum. When said nuts are loosened, the head may be withdrawn from the drum, the eyes f and bolts 85 e readily disengaging. This feature permits the head of the drum to be displaced and restored without removing the drum or beaters from their shaft B, or the latter from its bearings.

By displacing the crank or power wheel or pulley, releasing the top pieces of the bearings B', loosening the fastening of the wheel F, and removing the head of the drum, the shaft B and the beater may be conveniently and entirely withdrawn from the drum for the purpose of repairs, inspection, &c.

Having thus described my invention, what I claim as new, and desire to secure by Letters Patent, is—

1. A drum mounted on a reversely-rotating beater-shaft, in combination with a bevel-wheel rigidly connected with the head of said drum, and freely encircling said shaft, a bevel-

- wheel rigidly connected with said shaft, and an intermediate idler, the two bevel-wheels thus being on the same shaft, substantially as and for the purpose set forth. 15
5. 2. A drum mounted on a reversely-rotating beater-shaft, and having one head divided, in combination with ears connected with said head, bolts secured to the drum, and nuts fitted on said bolts, substantially as and for the purpose set forth. 20
- 10 3. A drum mounted on a reversely-rotating beater-shaft, and having at one end a divided head with the fastening bolts, eyes, and nuts, in combination with two bevel-wheels and an idler, both bevel-wheels being on the beater-shaft, one fixed thereto, and the other loose thereon, and fixed to the head of the drum, substantially as and for the purpose set forth.
4. A mixing-machine having a drum mounted on a reversely-rotating beater-shaft, and 20 beaters formed with cross-bars and end heads, the cross-bars alternating in adjacent beaters, substantially as and for the purpose set forth.

D. H. LEVETT.
